UNITED STATES PATENT OFFICE.

JOSEPH L. HUTCHINGS, OF OLEAN, NEW YORK.

DRAINING VALVE.

Application filed February 2, 1926. Serial No. 85,422.

This invention relates to a drain device and has for its object more particularly the provision of an improved draining valve for liquid or gaseous containers.

5 My improved draining valve is of the non-freezing variety, such as is described in my co-pending application, filed August 15, 1925, Serial No. 50,424, of which this application is a continuation in part.

10 That is to say, when the valve is installed and is in the closed position, there will be no contents of the container, to which the valve is to be attached, within the draining valve to freeze and thereby clog the same.

15 As soon as the valve is turned off, it drains itself substantially dry.

In order to make my valve easily non-leakable in the most difficult situations, I make use of both threads and ground seats 20 on the valve members. This combination is particularly advantageous when it is desired to use a draining valve in connection with liquids of exceedingly mobile qualities or with gases under high pressure.

25 Thus, I employ a stationary valve member having an axial passage therethrough. This member is preferably in two main parts. One part is to be attached to the inside of the container, while the other part 30 is to be attached to the outside of the container in axial alignment with the first part. A movable valve member is operatively connected to the inside stationary member part. A vent leads to the axial passage, through 35 the stationary member, through which is conducted the contents of the container when the valve is in the open position.

The cooperating movable and stationary members are both threaded and ground seated in some appropriate manner so that the movable member can be drawn relatively to the stationary member to open and close the vent. The ground seats make very close contact when the movable member is tightly drawn toward the stationary member by 40 means of the threads. Moreover, the mutually tight fitting threads on the valve members tend to keep the ground seats tightly contacting with one another when 45 the valve is in the closed position.

50 Suitable means are provided at the end of the outside stationary member part, as a turning wheel or bar attached to a stem leading through the axial passage and fitting into the cap end of the movable member, for moving the movable member rela-

tively to the stationary member to open and close the vent or vents. These turning means may be either permanently attached or detachable. In order to make the valve safer 60 and more fool-proof, it is preferable to have the turning means detachable. If, after the valve is closed, these turning means are detached, it will be impossible to again open the valve until a key has been found to fit 65 the particular construction of the movable member socket designed to receive the turning means.

In order that the contents of a container, as in the case of an oil tank, may be drained 70 at different levels, adjustable means are provided for conducting the contents from any desired level, to the draining valve attached to the container.

My improved drain valve will be more 75 clearly understood by reference to the accompanying drawings, taken in connection with the following description, in which:

Fig. 1 is a sectional elevation of a valve attached to a container, showing the valve 80 in the closed position.

Fig. 2 is a sectional elevation of the same valve in the open position.

The movable member 1, preferably made of brass, is appropriately threaded for a 85 short distance 2, adjacent to the ground seat 3. This movable member has a suitable pocket or socket 4, into which a wrench or turning means can be inserted. The ground seat 3 is carefully threaded to fit snugly 90 upon the ground seat of the stationary member.

The stationary member part 5 is appropriately threaded over a distance 6, so that the movable member 1, may be screwed back 95 and forth over the vent 7 leading to the axial passageway 8. This stationary member part 5, attached to the inside of the container, is appropriately ground seated at 9 to fit the companion ground seat 3 on the 100 movable member. A shoulder 10 is provided on the stationary member part, preferably cast on the same, which is threaded at 11, to receive the feeding cylinder 12. The threaded end 13 is designed to fit into 105 the pipe flange 14 secured to the container 15 by means of the rivets 16. The lock washer 17 is used to draw the stationary member part 5 so tightly into the pipe flange 14, that the same will remain immovable during the turning of the movable member. 110

The feeding cylinder 12 is of such dimensions as to completely cover the movable member 1 in its closed as well as in its open position. It is preferably of such length that the closed end of the movable member will bear against the closed end of this cylinder when the movable member is in the open position. In this manner the complete disengagement of the movable member from the stationary member part can be avoided. An adjustable conduit 18, preferably a metallic pipe, although a rubber hose could be used, is connected to the feeding cylinder 12 by means of the elbow 19, appropriately screwed into the feeding cylinder. The elbow 19 fits loosely into the cylinder so that the pipe conduit 18 may be lifted or lowered to any desired level within the container.

A hole 20 is placed in the container 15 in line with the axial passageway of the stationary member part 5 within the container, as well as the stationary member part 21, attached to the outside of the container. One end of the outside stationary member part 21 is threaded at 22 to fit snugly and leakably into the pipe flange 23, attached to the container 15 by means of the rivets 16.

The other end of the outside stationary member part is threaded at 24 to receive the T 26. An outlet pipe 27 fits into the lower portion of the T .

The other end of the T is fitted with a bushing 28 containing packing material 29, over which is screwed the bushing cap 30.

A turning wrench or stem 31 equipped with a head 32, designed to fit into the socket 4 of the movable member 1, makes up one end thereof. This turning stem 31 is equipped at the other or outside end thereof with a turning rod or wheel 33. While this turning stem may be permanently attached to the movable member 1, it is preferable to have it detachable, so that the main body of the stem can be completely withdrawn from the axial passageway of the stationary member (comprising the inside and outside stationary member parts). In this manner an unimpeded passageway is provided for the inflowing contents of the container, when the movable member of the draining valve is in the open position. Moreover, in order to make this draining valve substantially fool-proof the bushing 28 may be completely removed, along with the turning stem, from the T 26. It is thus apparent that it will be impossible to turn the movable member within the tank, unless a turning stem is found with a head exactly designed to fit into the socket 4.

The operation of my improved draining valve is as follows:

Assuming that the container 15 is filled with a liquid or gas, and it is desired to drain off some of its contents, the turning stem head 32 is pushed into the socket 4,

of the movable member 1. An appropriate number of turns will put the movable member 1 beyond the vent 7 in the stationary member part 5.

As soon as the vent 7 is open, the contents of the container, passing down through the adjustable conduit 18, floods the interior of the feeding cylinder 12, and the same rushes down into the axial passageway 8.

In order to provide a more free and unimpeded passageway for the outflow of the contents of the container, the turning stem 31 is preferably withdrawn as far as possible. That is, until the head 32 strikes against the bushing 28. The contents of the container then flow through the axial passageway into the T 26 and down the outlet pipe 27.

After a suitable amount of the contents of the container have been withdrawn, the detachable stem 31 is again shoved back into the socket 4 of the movable member 1. An appropriate number of turns in the reverse direction again puts the draining valve in the closed position. If desired, the bushing 28 may be removed from the T 26, which will also carry with it the turning stem 31. A plug of any conventional make may then be inserted into the end of the T left open by the removal of the bushing, in order to close the same.

The use of the feeding cylinder 12 is optional. This feeding device is merely provided for those situations in which it is desirable to withdraw contents of the container from different levels. Let us suppose that the container is filled with oil and water. Since oil will float upon water, the container will have at least two strata of liquids—one of water and the other of oil. If the operator wishes to remove oil, and not water, he merely pulls the adjustable conduit 18 up to the oil stratum. When that is done, oil can be withdrawn from the tank as soon as the draining valve is put into the open position.

It is to be understood that my invention is not to be confined to the one single form of valve that I have illustrated in the accompanying drawings and described in this specification. Variations of structure are possible without deviating from the principles or spirit of my discovery. I have made use of the combined features of threads and ground seats in a draining valve of the non-freezing variety.

I claim:

1. A draining valve comprising, a stationary member with an axial passage therethrough, a movable member operatively connected to the stationary member, a vent leading to said axial passage, said members being both threaded and ground seated one to receive the other, and means for moving the movable member relatively to the sta-

tionary member to open and close the vent, the ground seats being in engagement when the valve is closed.

2. The combination of a container, a stationary valve member with an axial passage therethrough, a movable valve member operatively connected to the stationary member, a vent leading to said axial passage, said members being both threaded and ground seated one to receive the other, and means for moving the movable member relatively to the stationary member to open and close the vent, the ground seats being in engagement when the valve is closed.

15 3. The combination of a container, a stationary valve member with an axial passage therethrough, a movable valve member operatively connected to the stationary member, a vent leading to said axial passage, said members being both threaded and ground seated one to receive the other, adjustable means for conducting contents of the container from different levels to the vent, and means for moving the movable member relatively to the stationary member to open and close the vent, the ground seats being in engagement when the valve is closed.

25 4. A draining valve comprising, a stationary member with an axial passage there-

through, a movable member operatively connected to the stationary member, a vent leading to the axial passage, said members being both threaded and ground seated one to receive the other, means to prevent the complete disengagement of the movable and stationary members, and means for moving the movable member relatively to the stationary member to open and close the vent, the ground seats being in engagement when the valve is closed.

40 5. A draining valve comprising a stationary member with an axial passage therethrough, a movable member operatively connected to the stationary member, a vent leading to said axial passage, said members being both threaded and ground seated one to receive the other, and means for moving the movable member relatively to the stationary member to open and close the vent, including a detachable wrench which may 45 be withdrawn from the main passageway to allow a free drainage through the valve, the ground seats being in engagement when the valve is closed.

50 In testimony whereof I affix my signature.

JOSEPH L. HUTCHINGS.
